ELASTIC-BAND-SUPPORTING FRAME FOR USE IN A GAME

Donald J. Rodemeyer, Cliffside Park, N.J., assignor to
Ideal Toy Corporation, Hollis, N.Y.

Filed Oct. 15, 1970, Ser. No. 25,514

Claims priority, application Canada July 21, 1970

Term of patent 14 years

Int. Cl. D21—01

U.S. Cl. D34—5

FIG. 1

FIG. 2

FIG. 3

FIG. 4

FIG. 1 of the drawing is a perspective view of an elastic-band-supporting frame for use in a game embodying my new design.

FIG. 2 is an elevational view of said frame as seen from the front, rear or side.

FIG. 3 is a top plan view of said frame, and FIG. 4 is a bottom plan view of said frame.

I claim:

The ornamental design for an elastic-band-supporting frame for use in a game, substantially as shown and described.
